GOLF CLUB HEAD OR THE LIKE

Harry M. Brill, Chicago, Ill., assignor to Nat Rosasco, Le Roy Rosasco, and Nat Rosasco, Jr., a co-partnership doing business as Northwestern Golf Company

Filed Nov. 28, 1962, Ser. No. 72,637

Term of patent 14 years

(Cl. D34—5)

The bottom of the club head is plain and unornamented.

I claim:

The ornamental design for a golf club head or the like, substantially as shown and described.
